UNITED STATES PATENT OFFICE.

JEAN BAPTISTE GUSTAVE ADOLPHE CANET, OF PARIS, FRANCE, ASSIGNOR
OF ONE-HALF TO SIR JOSEPH WHITWORTH & CO., (LIMITED,) OF MAN-
CHESTER, ENGLAND.

GUN-CARRIAGE.

SPECIFICATION forming part of Letters Patent No. 425,656, dated April 15, 1890.

Application filed July 7, 1888. Serial No. 279,250. (No model.) Patented in France March 6, 1886, No. 174,597, and in
England July 9, 1887, No. 9,686.

To all whom it may concern:

Be it known that I, JEAN BAPTISTE GUSTAVE ADOLPHE CANET, engineer, a citizen of the Republic of France, and a resident of Paris, France, have invented new and useful Improvements in and Relating to Gun Carriages or Mountings, (for which I have obtained patents in Great Britain, No. 9,686, dated July 9, 1887, and in France, No. 174,597, dated March 6, 1886,) of which the following is a specification, reference being had to the accompanying drawings.

This invention relates to gun carriages or mountings for either land or sea service.

An important feature of the said invention is the construction of a gun carriage or mounting with a rocking arm or lever on which the gun is secured, so that in recoiling and returning to the firing position it moves with the said lever about the fulcrum or pivot thereof without changing its position relatively thereto, and which is arranged in combination with brake and recuperator apparatus, as and for the purposes hereinafter explained.

Another feature of my said invention is the provision for elevating and depressing the gun by adjusting the fulcrum-pin or pivot-pin of the said rocking lever.

My said invention, moreover, comprises other improvements, hereinafter set forth.

In the accompanying drawings I have shown how my said invention may be conveniently and advantageously carried into practice.

Figure 1 is a vertical longitudinal central section of one form of my improved gun-mounting with the gun in a horizontal position, some of the parts being shown in side elevation. Fig. 2 is a rear elevation of the said mounting; and Fig. 3 is a vertical longitudinal central section thereof with the gun at its greatest angle of elevation, some of the parts being shown in side elevation.

Like letters indicate corresponding parts throughout the drawings.

A is a base-plate or racer, which serves also as a pivot.

B is a platform or turn-table, which is supported upon the said base-plate or racer by

means of rollers C, fitted to rotate upon pins 50 C', fixed in the said platform or turn-table, or by means of a circular series of balls or otherwise. A strong screw-shaft D is fitted to rotate in bearings D' D², formed with or firmly attached to the platform or turn-table 55 B. This screw-shaft is provided with a hand-wheel D³, whereby it may be rotated for the purpose hereinafter specified, endwise travel or movement of the said screw-shaft being prevented by fixed collars or shoulders D⁴ or 60 by a thrust-bearing or by other suitable means. To the said screw-shaft D is fitted a nut E, supported upon an inclined plane or surface B' on the platform B in guides B*, Fig. 2, in which it slides when the said screw-shaft is rotated.

The gun F is supported and held by its trunnions in the upper or outer end of a rocking lever G, the fulcrum-pin or pivot-pin II of which is carried by the sliding nut E. The 70 gun rests in a cradle or transom G', forming a part of the lever G, or is otherwise so arranged that the said gun and lever will move together while maintaining the same position relatively to each other—that is to say, in its recoil and in its return to the firing position the gun will move with the lever about the fulcrum or pivot II without angular movement relatively to the said lever, as herein-after described.

I is the cylinder of the hydraulic brake apparatus, which cylinder is provided with trunnions I', whereby it is mounted in bearings B² in a frame or standards B³, formed with or firmly attached to the platform or turn-table 85 B. The said cylinder is therefore free to rock or oscillate as and for the purpose hereinafter specified. The cylinder I has a piston I², the rod I³ of which is jointed or pivoted at I⁴ to the rocking lever G. The said 90 brake has combined with it recuperator apparatus for returning the gun to the firing position after its recoil. This recuperator apparatus consists of a spring J', preferably a so-called "Belleville" spring, which is enclosed in a cylinder or casing J, formed with or firmly attached to the cylinder I, and through which is passed a rod J², arranged to

act upon and be acted upon by the said spring through the medium of a disk or washer J^3 and locking-nuts $J^4 J^5$ or other suitable devices. The said rod J^2 is coupled or connected by means of a link J^6 to the rocking lever G . The said brake apparatus is preferably so constructed that it will serve as a hydraulic buffer for preventing or diminishing shock or concussion at the termination of the recoil or return movement of the gun like those described in the specification of another application for Letters Patent of the United States filed by me.

The platform B is provided with one or more hooks or clips K , which engage with a flange A' on the base-plate or racer A and prevent tilting of the said platform. The said platform can be rotated to train or traverse the gun by any suitable means. A claw L is pivoted at L' to a bracket formed with or firmly attached to the said platform, and is adapted to grip or bear upon the flange A' of the base-plate or racer A . This claw is provided with a socket L^* for the reception of a lever L^2 , whereby sufficient pressure may be exerted upon the flange A' to hold the frame or platform B in any position to which it may be adjusted, and thus prevent horizontal movement of the gun while firing. This lever may also be used for training the gun.

L^3 is a pin, which may be secured to the base-plate A by means of a chain L^4 or otherwise, and which, when the gun is housed, is to be inserted in a hole in the said base-plate and into a corresponding hole in the turn-table B for the purpose of preventing accidental movement or displacement of the gun by rotation of the turn-table—for example, during the rolling or pitching of a ship or vessel on the deck of which the gun is mounted.

The claw L and the flange A' of the base-plate A are sometimes provided with teeth or serrations, or are otherwise roughened to facilitate the holding of the platform or turn-table in position by means of the said claw.

When the gun recoils, it turns (or tends to turn) with the rocking lever G in a vertical plane upon or about the pivot or fulcrum H , the recoil movement being resisted and its amplitude limited by the hydraulic brake. In this recoil movement the brake and recuperator apparatus turns upon or about the trunnions I' , and thus adapts itself to the angular changes of position of the rocking lever. The spring J' in the recuperator-cylinder J is, moreover, compressed, so that at the termination of the said recoil movement the said spring will react to return the gun to the firing position. Throughout the recoil and return movement the gun, as above stated, retains its position relatively to the rocking lever—that is to say, it does not turn upon or about its trunnions. The vertical pointing or elevation of the gun is effected as follows—that is to say, by means of the hand-wheel D^3 the screw-shaft D is rotated to move

the sliding nut E endwise in either direction. The rocking lever G , the gun, and the cylinders $I J$ are thereby moved upon or about the trunnions I' of the hydraulic cylinder I in the same vertical plane in which the gun and lever move in the recoil and in the return to the firing position.

The position which the gun and rocking lever occupy when at the extreme limit of recoil are indicated by dotted lines in Figs. 1 and 3, those in Fig. 1 showing the limit of recoil from the horizontal firing position, and those in Fig. 3 the limit of recoil when the gun is fired at its greatest angle of elevation.

By mounting the brake and recuperator on trunnions, so that they can move in correspondence with the rocking lever G , and by having the rod J^2 of the recuperator apparatus connected to the said lever, as above described, I avoid all stress tending to bend the said rods and obtain a very compact and convenient arrangement of the brake and recuperator apparatus relatively to the rocking lever G .

An important advantage of the above-described improved construction is that the chief effect which the recoil has upon the base-plate or racer is a simple horizontal or nearly horizontal stress or pressure transmitted to it through the fulcrum-pin H of the rocking lever G . Therefore my improved carriage or mounting is very advantageous for use on light structures.

The turn-table or platform B and the frame thereon are usually arranged to support a mantlet or shield for protecting the gunner and the gun-mounting.

It is obvious that the above-described apparatus can be somewhat modified without departing from the nature of the said invention. For instance, other apparatus might be substituted for the screw and sliding nut for adjusting the fulcrum-pin of the rocking lever to elevate or depress the gun. Other means than those above described may be employed for training or traversing the gun and for retaining the same in any position to which it may be adjusted and preventing accidental movement or displacement of the gun when housed. Any well-known or suitable brake apparatus may be substituted for that hereinbefore referred to. Other suitable springs may be substituted for the Belleville disks shown in the drawings, or a recuperator operating by the compression and expansion of air may be used for returning the gun to the firing position after its recoil. Moreover, although I have shown in the drawings a gun provided with trunnions, it is evident that the rocking lever may be adapted for holding a gun without trunnions.

What I claim is—

1. In a gun-mounting, the combination of a rocking arm or lever in which the gun is supported, a pivot or fulcrum about which the said lever turns with the gun in a vertical plane, and an adjusting device for moving

- the said pivot or fulcrum in an inclined path in the same vertical plane, for the purpose above specified.
2. In a gun-mounting, the combination of 5 a rocking arm or lever in the upper end of which the gun is supported, a pivot or fulcrum at the lower end of the said lever about which the said lever turns with the gun in a vertical plane, and an adjusting-screw for 10 moving the said pivot or fulcrum in an inclined path in the same vertical plane, for the purpose above specified.
3. In a gun-mounting, the combination of 15 a rocking arm or lever the upper end of which is adapted to carry the gun, and which is arranged to turn in a vertical plane about a pivot or fulcrum at its lower end, the said pivot being adjustable in the same vertical plane, and elastic devices whereby the said 20 arm or lever is coupled to the under carriage or turn-table, substantially as and for the purposes above specified.
4. In a gun-mounting, the combination of 25 a block or screw-nut adjustable in a vertical plane upon an inclined surface on the under carriage or turn-table and a rocking arm or lever pivoted at its lower end to the said block or nut and adapted to carry the gun in its upper end, substantially as and for the 30 purpose above specified.
5. In a gun-mounting, the combination of 35 a block or screw-nut adjustable in a vertical plane upon an inclined surface on the under carriage or turn-table, a rocking arm or lever pivoted at its lower end to the said block or nut and adapted to carry the gun in its upper end, and elastic devices connecting the said arm or lever at an intermediate point to the under carriage or turn-table, so that the gun 40 without changing its angle relatively to the said lever will recoil and return to its firing position in the said vertical plane about the pivot or fulcrum of the said arm or lever, substantially as described.
6. In a gun-mounting, the combination of 45 a screw-nut arranged to slide in a vertical plane upon an inclined surface on the under carriage or turn-table, a screw-shaft working in the said nut and fitted to rotate but re- 50 strained from endwise motion in bearings in the said under carriage or turn-table, and a rocking arm or lever pivoted at its lower end to the said nut and adapted to carry the gun in its upper end, substantially as and for the 55 purposes above specified.
7. In a gun-mounting, the combination of 60 a screw-nut arranged to slide in a vertical plane upon an inclined surface on the under carriage or turn-table, a screw-shaft working in the said nut and fitted to rotate but re- 65 strained from endwise motion in bearings in the said under carriage or turn-table, a rocking arm or lever pivoted at its lower end to the said nut and adapted to carry the gun in its upper end, and elastic devices connecting the said arm or lever at an intermediate point 70 to the under carriage or turn-table, substantially as and for the purposes above specified.
8. In a gun-mounting, the combination, 75 with a rocking arm or lever adapted to carry the gun in its upper end and pivoted at its lower end to a screw-nut adjustable in a vertical plane upon an inclined surface on the under carriage or turn-table, of a hydraulic recoil-brake the cylinder of which is supported by trunnions in bearings in the under carriage or turn-table and the piston-rod of which is coupled to the said rocking arm or lever, substantially as and for the purposes 80 above specified.
9. In a gun-mounting, the combination, 85 with a rocking arm or lever adapted to carry the gun and pivoted to a block or screw-nut adjustable in a vertical plane upon an inclined surface on the under carriage or turn-table, of a hydraulic recoil-brake coupled to the said rocking arm or lever and to the under carriage or turn-table, and an elastic device, also coupled to the said rocking arm or lever and to the under carriage or turn- 90 table, substantially as and for the purposes above specified.
10. In a gun-mounting, the combination, 95 with a rocking arm or lever adapted to carry the gun in its upper end and pivoted at its lower end to a screw-nut adjustable in a vertical plane upon an inclined surface on the under carriage or turn-table, of a recuperator comprising a box or cylinder arranged to turn about trunnions held in bearings in the under carriage or turn-table, a rod coupled to the said rocking lever, and a spring inclosed in the said box or cylinder and bearing against one end thereof and against a shoulder, collar, or disk on the said rod, substantially as 100 and for the purposes above specified.
11. In a gun-mounting, the combination, 105 with a rocking arm or lever adapted to carry the gun and pivoted to a screw-nut adjustable in a vertical plane upon an inclined surface 110 on the under carriage or turn-table, of a hydraulic recoil-brake the cylinder of which is supported by trunnions in bearings in the under carriage or turn-table and the piston-rod of which is coupled to the said rocking arm 115 or lever, and a recuperator comprising a box or cylinder attached to the brake-cylinder, a rod which is coupled to the said rocking arm or lever and provided with a shoulder, collar, or disk, and a spring inclosed in the said box 120 or cylinder and bearing against one end thereof and against the said shoulder, collar, or disk, all substantially as and for the purposes 125 above specified.
12. The combination of an under carriage 130 or turn-table, a rocking lever, a sliding nut to which the said lever is pivoted, a screw-shaft carried in bearings in the said under carriage or turn-table for adjusting the said nut, a hydraulic brake the cylinder of which is mounted upon trunnions in bearings in the under carriage or turn-table and the piston-

rod of which is coupled to the said rocking lever, and a recuperator carried by the brake-cylinder and comprising a rod acted upon by springs and coupled to the said rocking lever, 5 substantially as and for the purposes set forth.

13. The combination of the base-plate A, the under carriage or turn-table B, supported thereon through the medium of rollers, the screw-shaft D, carried in bearings on the under carriage or turn-table, the nut E, fitted to the said screw-shaft and arranged to slide upon the inclined surface B', the rocking lever G, pivoted to the said nut, the brake I and recuperator J, supported by trunnions I' upon the under carriage or turn-table and having their rods I³ J² coupled to the said rocking lever, and the claw or clip L, pivoted at L' to 25 the under carriage or turn-table and adapted to receive the lever L², all substantially as and for the purposes set forth.

15 I' upon the under carriage or turn-table and having their rods I³ J² coupled to the said rocking lever, substantially as and for the purposes set forth.

14. The combination of the base-plate A, the 20 under carriage or turn-table B, supported

thereon through the medium of rollers, the screw-shaft D, carried in bearings on the under carriage or turn-table, the nut E, fitted to the said screw-shaft and arranged to slide upon the inclined surface B', the rocking lever G, pivoted to the said nut, the brake I and recuperator J, supported by trunnions I' upon the under carriage or turn-table and having their rods I³ J² coupled to the said rocking lever, and the claw or clip L, pivoted at L' to 30 the under carriage or turn-table and adapted to receive the lever L², all substantially as and for the purposes set forth.

In testimony whereof I have hereunto signed my name in the presence of two sub- 35 scribing witnesses.

JEAN BAPTISTE GUSTAVE ADOLPHE CANET.
